SWINGABLE BACK FOR LOUNGES AND CHAIRS

Filed Oct. 19, 1925

93 Inventor:
John J. Hogan.
By L/G Fletcher Atty

Patented Oct. 26, 1926.

1,604,825

UNITED STATES PATENT OFFICE.

JOHN J. HOGAN, OF ST. LOUIS, MISSOURI.

SWINGABLE BACK FOR LOUNGES AND CHAIRS.

Application filed October 19, 1925. Serial No. 63,295.

This invention relates to improvements in the swingable backs for lounges, chairs and the like, and has for its primary object the purpose of providing improved means 5 for operating and adjusting the chair back.

Another object of the invention is in providing an improved arresting or holding means for holding the adjustment of the chair back or back-rest.

10 A further object of the invention is in providing the back-rests of chairs with an improved back-rest operating and adjusting means which will permit the back-rest to be swung downwardly upon the seating cushion so that the chair or lounge can be condensed in size for shipping or storage.

A still further object of the invention is in providing the swingable chair or lounge back with an automatic closure portion for 20 closing the gap or space provided between the lower end of the chair back and the chair base for permitting swinging movement of the back.

Other and further objects will appear in 25 the specification and be specifically pointed out in the appended claims, reference being had to the accompanying drawings, exemplifying the invention, and in which:—

Figure 1 is a side elevation of a portion 30 of a chair or lounge showing this improved mechanism used in connection with the swingable back.

Figure 2 is a fragmentary transverse vertical section taken on the line II—II of 35 Fig. 1.

Figure 3 is an enlarged view of one of the arresting levers showing an adjustable stoppin therefor.

Figure 4 is an enlarged detailed view of 40 the adjusting mechanism.

Referring by numerals to the accompanying drawings, 1 designates a side sill of the chair or lounge, and 2 is one of the legs for supporting the sill, and extending upwardly 45 from the sill 1 is one of the usual pair of arms 3.

For the purpose of illustration only one 50 of a pair of operating mechanisms is shown, the other mechanism being a duplicate of the mechanism hereinafter described, and in which a standard 4 having a horizontally extending portion 5 is secured to the sill 1, said extending portion having a pair of horizontally and inwardly extending lips 6 55 for the support of an angle iron cross-member 7.

Horizontally disposed adjacent the upper end of the standard 4 is a bolt 8, and swingable on said bolt inwardly of said standard is a segment 9 having interiorly extending 60 teeth 10, and extending upwardly from said segment is an arm 11 which is secured to one of the side members of the chair back 12, and extending from said segment to the oppositely disposed segment not shown, is 65 a tie rod 13.

Pivoted at 14 to the extending portion 5 of the standard 4 is an arresting lever 15 having a downwardly extending portion 16, and secured to the lower end of said portion 16 is a tie rod 17 which extends transversely across the approximate width of the chair and is secured at its opposite end at 18 to the depending portion 19 of the oppositely disposed arresting lever 20. Secured to 70 the forward end of the lever 15 as designated at 21, is a pull lever 22 having a horizontally disposed outwardly extending hand engaging portion 23 which extends over the sill 1, the oppositely disposed arresting lever 20 being provided with a similar hand engaging portion.

Pivoted at 24 to the segment 9 is a lever 25 having a slot 26 formed in its lower end 85 27, and slidable within said slot is a pivot 28 of a lever 29, said lever being turnable on a shaft 30 and is adapted to be acted on as well as being active upon a tension spring 31 which is mounted upon the shaft 30, said shaft being supported in the bearings 32. 90

Extending rearwardly from the standard 4 is an ear 33 bearing a pivot 34, and mounted on said pivot is a lever 35 having a cross-member 36 secured thereto at its lower end, said lever being spring actuated downwardly by the spring 37 which is mounted upon the pivot 34, and secured at one end to the ear 33.

The cross-member 36 is adapted to rest upon the cross sill 38 of the chair, and secured to the cross-member 36 is the back covering fabric 39 of the chair back 12, said fabric covering being flexed as shown in Fig. 1 when the chair back is in a position inclining rearwardly from the vertical. 100

The extending portion 5 of the standard 4 is provided with a bracket 40 which is disposed above the sill 1, said bracket having a horizontal projection, and mounted upon said projection is a coil spring 41 having 110 one end in engagement with the arresting lever 15 for applying pressure downwardly

on said lever, and extended horizontally from said lever forwardly of the depending portion 16 thereof, is a stop pin 42 for engagement with the respective notches 43, which are provided by the teeth 10 of the segment 9.

From an inspection of Fig. 1 it will be noted that the chair back 12 which is secured to the segment 9, is pivoted to the standard 10 4 by the bolt 8, and if pressure is brought to bear rearwardly against said back, said back will be prevented from being moved rearwardly by the pin 42, which is engaged in the forward notch 43 of the segment 9, 15 the exerted pressure creating a pulling strain on the arresting lever 15 which is pivoted at 14. When it is desired to swing the back rearwardly, the hand engaging portion 23 of the pulling member 22 upon being pulled 20 upwardly will cause the arresting lever 15 to be swung upon its pivot 14, thereby elevating the stop pin 42 of said lever from engagement with the notch 43, and the lever 15 is held in disengaged position until the 25 back 12 is swung rearwardly to a desired position, and the lever 15 is then permitted to be lowered by the action of the spring 41 thereagainst, and in which the stop pin 42 will engage a notch 43 of the segment 30 9 thereadjacent, and in which the back 12 will be held in the desired position.

In operating the back 12 rearwardly in which the segment 9 will be swung downwardly on the bolt or pivot 8, the lever 25 35 pivoted at 24 to said segment will bear against the pivot 28 of the lever 29 thereby moving said lever 29 forwardly, and in which the spring 31 will be wound and the tension thereof increased. In this connection when it is desired to have the back 12 moved to or towards an upright position, when the lever 15 is elevated by engaging 40 and lifting on the hand engaging portion 23 for the purpose of releasing the stop pin 45 42 of said lever from engagement with the notch 43, the spring 31 will become active on the spring clutch collar 44, and the lever 29 will be forced rearwardly by the spring tension and the pivot 28 of said lever will 50 become active on the lever 25, and in which the back 12 will be swung upwardly.

Inasmuch as there will always be an exposed gap between the bottom edge 45 of the back and the sills 1 of the chair, the 55 fabric covering 39 depending from the seat back which is secured at its lower end to the cross-member 36, will automatically close the gap as the spring tension on the levers 35 will hold the cross-member down upon 60 the cross sill 38. This arrangement of the fabric 39 always being extended to the cross sill 38 will present a pleasing appearance to the back when viewed from the rear.

For shipping or storage of articles of 65 furniture of this character, the back 12 can

be swung forwardly and downwardly without removing screws or any part of the structure by elevating and releasing the lever 15, and swinging the back 12 to the horizontal position shown in dotted lines 70 in Fig. 1 and in which the fabric 39 will be drawn taut by the action of the spring pressed levers 35 as the cross-member 36 leaves the cross sill 38. This arrangement of folding the back against the cushion of 75 the chair will aid in space economy.

In mounting the segments 9 on each side of the seat back, it sometimes occurs that the teeth of one segment are not in alignment with the teeth of the opposing segment, and inasmuch as the stop pins of the respective arresting levers 15 and 20 are to co-operate with the teeth of respective segments, provision is provided on the lever 20, whereby the pin 46 can be adjusted. 80 In this connection the pin 46 is mounted on a base 47, and secured to the lever by bolts 48 which are passed through respective slots 49 formed in the lever 20.

Inasmuch as the arresting levers 15 and 20 are tied together by the rod 17, the elevating or lowering of either lever by engaging and operating either the left or right hand engaging portion 23, both of said levers will be simultaneously moved and a release 95 or engagement will be made relative to both of the segments 9.

The outer bearing 32 adjacent which the lever 29 is mounted is provided with a lug 50 which is in the path of rearward travel of 100 the lever 29, said lever (or pair of levers) engaging against respective lugs 50 after the back 12 has been moved to its farthest upwardly inclined position as shown in Fig. 1, the lugs 50 holding the respective 105 levers 29 in inactive positions against respective levers 25 through the pivots 28 of the levers 29.

In order to permit the stop pins of respective levers 15 and 20 to ride over the 110 teeth 10 of respective segments when the back 12 is being swung, and particularly when the back is being swung to a horizontal position above the cushion of the chair, the segment is made open at its front end, 115 the circular portion 51 of the segment being reinforced or supported by the offset rib 52 which is formed integral with the segment.

What I claim is:—

1. An article of furniture having a back, 120 a pivoted segment bearing a series of interiorly arranged teeth secured to the lower end of said back, an arresting lever having a portion for co-operation with the teeth of said segment, releasing means for said lever, 125 a spring actuated lever, and a lever pivoted to said segment co-operable with said spring actuated lever.

2. A chair having a swingable back and a cross sill forming a part of the chair base, 130

- a length of fabric material depended from the back rearwardly thereof, means for holding the lower end of the fabric material downwardly against said cross sill during the rearward swinging of said back, and means provided whereby the holding down means of said material are elevated when said back is inclined forwardly of the chair base.
- 10 3. An article of furniture having a back, a pivoted segment bearing a series of teeth secured to the lower end of said back, an arresting lever having a portion for co-operation with the teeth of said segment, releasing means for said lever, a spring actuated lever, and a lever pivoted to said segment co-operable with said spring actuated lever, 35 said lever which is pivoted to said segment providing for said back being swung to an approximate horizontal position over the seating portion of the article.
- 13 4. An article of furniture having a back, a pivoted segment bearing a series of teeth secured to the lower end of said back, an arresting lever having an adjustable portion for co-operation with the teeth of said segment, releasing means for said lever, a 40 spring actuated lever, and a lever pivoted to said segment co-operable with said spring actuated lever.
- 16 5. An article of furniture having a back, a pivoted segment bearing a series of teeth secured to the lower end of said back, an arresting lever having an adjustable portion for co-operation with the teeth of said segment, releasing means for said lever, a 45 spring actuated lever, and a lever pivoted to said segment co-operable with said spring actuated lever.
- 19 6. An article of furniture having a back, a pivoted segment bearing a series of teeth secured to the lower end of said back, an arresting lever having an adjustable portion for co-operation with the teeth of said segment, releasing means for said lever, a 50 spring actuated lever, and a lever pivoted to said segment co-operable with said spring actuated lever.
- 22 7. An article of furniture having a back, a pivoted segment bearing a series of teeth disposed adjacent each side of said back at the lower end thereof, an arresting lever for co-operation with a respective segment, one of said levers having an adjustable portion for co-operation with the teeth of its co-operable segment, releasing means for said levers, a pair of spring actuated levers, and a lever pivoted to each of said segments for co-operation with a respective spring actuated lever.

JOHN J. HOGAN.
